UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,276,772.

Specification of Letters Patent. Patented Aug. 27, 1918.

Application filed May 24, 1917. Serial No. 170,603.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone ex- 10 change systems, and more particularly to such systems of the central energy type.

While it has been recognized that it is desirable to provide means by which a subscriber, connected with a central office link 15 circuit, might, under certain circumstances, attract the attention of the central office operator without the necessity of repeatedly moving the switchhook up and down, the means provided for obtaining this object has 20 resulted in confusion of signals to the operator. It is well known that a subscriber initiating a call causes the continuous operation of a line signal, which signal is an indication to the operator that some action upon 25 her part, for the benefit of the subscriber, is called for. In the systems heretofore used, the attention of the operator is attracted by a connected subscriber through the intermittent operation of the supervisory signal. It 30 will be seen, therefore, that the continuous operation of the line signal and the intermittent operation of the supervisory signal are both indications to the operator that some 35 act upon her part, for the benefit of the subscriber, is called for, and, therefore, some confusion results. It is the object of the 40 present invention to avoid this confusion, and to provide a system in which all the benefits derived from the systems heretofore used are retained.

In accordance with a feature of this invention, the supervisory signal of a link circuit, when connected with the telephone line, is controlled over the telephone line and 45 is intermittently operated to furnish a disconnect signal and continuously operated to furnish a recall signal. This continuous operation of the supervisory relay to furnish a recall indication is an indication of the 50 same character as that furnished by the continuous operation of a line signal; that is, both are indications to the operator that some act on her part, for the benefit of the subscriber is called for. On the other hand, 55 the disconnect signal, which is not an indi-

cation calling for an act for the benefit of the subscriber, may, therefore, very properly be of a different character from the recall indication.

In accordance with another feature of this invention, should the link circuit be connected with the telephone line as a calling line and the listening key be in its normal position, the supervisory signal will be continuously operated to serve as another indication to the operator that an act on her part, for the benefit of the subscriber, is called for. 60 65

It will be observed, therefore, that whenever an act on the part of the operator for the benefit of the subscriber is called for, the signal indication of the proper signaling device is the continuous operation thereof, whereas, when some act, which is not for the benefit of the subscriber, is called for, the 70 75 indication is the intermittent operation of a signaling device. In this way all confusion of signals is avoided.

For a more complete understanding of this invention, reference should be had to the 80 following description, taken in connection with the accompanying drawing, wherein is shown a telephone exchange system containing one embodiment of the invention.

All apparatus is shown in its normal and 85 unactuated condition. It is believed that an understanding of this invention may be gained from a description of the operation of the systems disclosed in the drawings and it will be so described.

There are shown two telephone lines A and B, which extend from subscribers' stations to a central office, at which is located a cord circuit C for interconnecting the telephone lines. The subscriber A, in initiating 90 a call, causes the lighting of the usual line lamp 5, and the operator, observing the lighted condition of this lamp, answers the call by inserting answering plug 6 of the cord circuit C into line jack 7, whereupon answering supervisory lamp 8 is lighted and cutoff relay 9 is operated over a circuit from battery through lamp 8, resistance 10, sleeve contacts of answering plug 6 and line jack 7, and the winding of cutoff relay 9 to 95 ground. The operation of the cutoff relay 9 disconnects line relay 11 from the telephone line A. Upon the connection of the answering plug of the cord circuit with the line jack of the telephone line, relays 15 and 100 105 110

16 are operated over a circuit from battery through winding 17 of repeating coil 18, winding of relay 15, ring contacts of the answering plug 6 and the line jack 7, over 5 one side of the line, through the station apparatus, back over the other side of the line, tip contacts of the line jack 7 and the answering plug 6, winding 19 of repeating coil 18, winding of relay 16, and normal 10 contact of relay 20 to ground. The operation of relay 15 would connect a resistance 21 in shunt with the lamp 8 were it not for the fact that relay 16 is operated, but since relay 16 is now actuated, the answering supervisory lamp 8 remains lighted to furnish a continuous signal indicating to the operator that some act upon her part for the benefit of the subscriber is required. The operator may now actuate listening key 22 to connect 15 the operator's telephone set to the cord circuit. A contact 23 is completed upon the actuation of the key 22, thereby completing a circuit for and causing the operation of relay 20, which, in operating, releases relay 25 16 and completes for itself a locking circuit, including its alternate contact. The release of relay 16 connects resistance 21 in parallel with the lamp 8, thereby effacing the lamp. The operator, upon being advised of the 30 number of the line with which connection is desired, for example, line B, restores the listening key 22 to normal position and connects the calling end of cord circuit C with line B. The subscriber on line B may be 35 signaled in any desired manner. In responding, the called subscriber removes the receiver from the switchhook, thereby causing the operation of calling supervisory relay 30. 40 At the conclusion of the conversation, subscribers A and B restore the receivers to the switchhooks. The restoration of the receiver to the switchhook by subscriber B causes the deenergization of supervisory relay 30. The restoration to the switchhook of the receiver by subscriber A causes the deenergization of relays 15 and 20, whereupon 45 the interrupter 32 and resistance 21 are connected in parallel with the lamp 8. Due to 50 the rotation of the interrupter 32, this parallel path is intermittently broken, thereby causing the intermittent operation of the supervisory lamp 8, which serves as a disconnect signal. 55 Should the subscriber A, before the answering plug 6 is withdrawn from the line jack 7, desire to initiate another call, the mere removal of the receiver from the switchhook causes the operation of relays 15 and 16, 60 which disconnects the interrupter from the circuit and permits the continuous operation of the supervisory lamp 8, which is an indication to the operator that an act upon her part, for the benefit of the subscriber, is required. The operator may now actuate the

listening key 22 to connect the operator's telephone set to the cord circuit, and in so doing causes the energization of relay 20 and the deenergization of relay 16. Upon being advised of the connection desired by 70 the calling subscriber, the connection may be established in the manner heretofore described.

What is claimed is:

1. A telephone exchange system comprising a telephone line, a link circuit connected therewith, a supervisory signaling device, a supervisory relay and a secondary relay for the link circuit, an interrupter brought into circuit relation with the signaling device 75 upon the deenergization of the supervisory and secondary relays to cause the intermittent operation of the supervisory signaling device to furnish a disconnect signal, and an operating circuit for the supervisory signaling device rendered effective upon the subsequent energization of the supervisory relay while the secondary relay is deenergized to cause the continuous operation of the supervisory signaling device to furnish a recall 90 signal.

2. A telephone exchange system comprising a telephone line, a link circuit, a signaling device for the link circuit, an operating circuit for the signaling device established upon connection of the link circuit with the telephone line as a calling line to cause the operation of the signaling device, an operator's telephone set, a listening key for connecting the operator's telephone set 95 with the link circuit, a relay responsive to the actuation of the key for stopping the operation of the signaling device, a supervisory relay for the link circuit, and an intermittently closed operating circuit for the signaling device established upon the deenergization of the supervisory relay to cause the intermittent operation of the signaling device.

3. A telephone exchange system comprising a telephone line, a link circuit, a signaling device established upon connection of the link circuit with the telephone line as a calling line to cause the operation of the signaling device, an operator's telephone 110 set, a listening switch for connecting the operator's telephone set with the link circuit, a relay responsive to the actuation of the switch for stopping the operation of the signaling device, a supervisory relay for the 115 link circuit, and an intermittently closed operating circuit for the signaling device established upon the deenergization of the supervisory relay and the first mentioned relay to cause the intermittent operation of the 120 signaling device.

4. A telephone exchange system comprising a telephone line, a link circuit, a signaling device for the link circuit, an operating circuit for the signaling device established 130

upon connection of the link circuit with the telephone line as a calling line to cause the continuous operation of the signaling device, an operator controlled switch, a relay energized upon the actuation of the switch for stopping the operation of the signaling device, a supervisory relay for the link circuit, and an intermittent operating circuit for the signaling device established upon the deenergization of the supervisory relay to cause the intermittent operation of the signaling device to furnish a disconnect signal.

5 5. A telephone exchange system comprising a telephone line, a link circuit, a signaling device for the link circuit, an operating circuit for the signaling device established upon connection of the link circuit with the telephone line as a calling line to cause the continuous operation of the signaling device, an operator controlled switch, a relay energized upon the actuation of the switch, a shunt circuit for the signaling device established upon the actuation of the relay to stop the operation of the signaling device,

10 20 25 30

25 a supervisory relay for the link circuit, and an interrupter included in the shunt circuit upon the deenergization of the supervisory relay to cause the intermittent operation of the signaling device to furnish a disconnect signal.

6. A telephone exchange system comprising a telephone line, a cord circuit, a supervisory lamp for the cord circuit, an operat-

ing circuit for the lamp completed upon connection of the cord circuit with the telephone line as a calling line to cause the continuous glow of the lamp, an operator's telephone set, a listening key for connecting the operator's telephone set with the cord circuit, a relay energized upon the actuation of the listening key, a shunt circuit for the lamp established upon the energization of the relay to efface the lamp, a supervisory relay for the cord circuit, and an interrupter included in the shunt circuit upon the deenergization of the supervisory relay to cause the intermittent glowing of the lamp.

7. A telephone exchange system comprising a telephone line, a cord circuit connected therewith, a supervisory lamp for the cord circuit, a supervisory relay and a secondary relay for the cord circuit, an interrupter in circuit relation with the supervisory lamp when the supervisory and the secondary relays are deenergized to cause the intermittent glowing of the supervisory lamp to furnish a disconnect signal, an operating circuit for the supervisory lamp rendered effective upon the subsequent energization of the supervisory relay while the secondary relay is deenergized to cause the continuous glowing of the supervisory lamp to furnish a recall signal.

In witness whereof, I hereunto subscribe my name this 22nd day of May A. D., 1917. 85
CHARLES W. KECKLER.
